UNITED STATES PATENT OFFICE.

EDWARD DANIEL MACFEE, JR., OF ROLLING HILL, VIRGINIA.

EMBOSSING-DIE.

SPECIFICATION forming part of Letters Patent No. 732,762, dated July 7, 1903.

Application filed March 8, 1902. Serial No. 96,572. (No model.)

To all whom it may concern:

Be it known that I, EDWARD DANIEL MACFEE, Jr., a citizen of the United States, residing at Rolling Hill, in the county of Charlotte 5 and State of Virginia, have invented a new and useful Embossing-Die, of which the following is a specification.

This invention relates to embossing-dies.

The object of the invention is to provide a 10 die which may in a ready and positive manner and without the employment of special machinery for the purpose be operated for embossing purposes; furthermore, to provide a ready means of adjustment of the die with 15 relation to the work to be embossed.

With these and other objects in view, as will appear as the nature of the invention is better understood, the same consists in the 20 novel construction and combination of parts 25 of an embossing-die, as will be hereinafter fully described and claimed.

In the accompanying drawings, forming a part of this specification, and in which like numerals of reference indicate corresponding 30 parts, there is illustrated one form of embodiment of the invention capable of carrying the same into practical operation, it being understood that the elements therein exhibited may be varied or changed as to shape, proportion, 35 and exact manner of assemblage without departing from the spirit thereof.

In the drawings, Figure 1 is a view in elevation, exhibiting a photograph card or mount with the die positioned thereon and ready to 35 be subjected to pressure to effect embossing. Fig. 2 is a view in longitudinal section, taken on the line 2 2, Fig. 1. Fig. 3 is a view in vertical section, taken on the line 3 3, Fig. 1. Fig. 4 is a perspective detail view of the die 40 with its parts separated and disposed in the order in which they are assembled.

Referring to the drawings, 5 designates the die-holding frame, comprising a base-bar 10, constituting a gage, and two guides 20 and 45 30, secured to the bar, forming an approximately U-shaped frame for receiving the die. The bar is by preference made thickest at its center and gradually thinned toward its extremities to permit ready lateral yielding of 50 the guide to facilitate insertion and removal of the die, presently to be described. The bar is provided at its terminals with upward-pro-

jecting ears 11 and 12 and opposite the ears with horizontally-extending lugs 13 and 14, which, as also the ears, are by preference 55 formed integral with the bar. The guides 20 and 30 are constructed of thin resilient metal and are riveted or otherwise rigidly attached at their lower ends to the inner faces of the ears 11 and 12, and being of less thickness than 60 the width of the base a ledge 15 is presented to engage with the edge of the card, as will presently appear. The guides are provided on their inner or opposed edges with a plurality of notches 21 and 31, which are disposed in parallel planes and are by preference 65 equally spaced apart, as shown in Fig. 4. The guides when the device is in operation are held from lateral yielding by a clamping-bar 40, which is preferably made from 70 thin sheet metal, having its ends formed into loops 41 and 42, suitably secured to the body of the bar, these loops being of a size snugly to fit the guides and to move thereon, as will be readily understood by reference to Figs. 75 1 and 4.

The die 50 comprises a plate bearing a cameo design and is provided at its ends on its front face with outwardly-extending flanges 51 and 52, which may be formed either integral with the die or be riveted or otherwise secured thereto, if desired, and the rear face of the die carries two similar outwardly-extending flanges 53 and 54, the latter being somewhat shorter than the flanges 51 and 52, 85 the two sets of flanges presenting terminal grooves 55 and 56, adapted to be engaged by the guides. Pins 57 and 58 are extended transversely across the grooves and are rigidly secured in the plates, these pins being 90 adapted to engage the notches 21 and 31 in the guides to hold the die in adjusted position with relation to the base-bar, the clamping-bar operating positively to prevent disconnection of the pins from the notches when the 95 die is in use.

In the use of the device, the die having been adjusted with relation to the base-bar to bring the design the desired distance above the edge of the card, the frame is disposed on the 100 card, as shown in Fig. 1, with the guide-bar and lugs 13 and 14 bearing against the edge of the card. The operator then grasps the frame and card between the thumb and fore-

finger and inserts the opposite end of the card between two rolls, such as the rollers of an ordinary burnishing-machine used by photographers, and the rollers are then turned 5 to feed the card forward to bring the terminals of the guides into contact with the rollers, whereupon the operator releases his hold on the frame and continues the operation until the card and frame have been fed from 10 between the rollers and the impression taken. The burnishing-rollers are usually hot when in use, and this heat being transmitted to the die will cause it to impart a darkened hue to the imprint, thus to cause it to stand out 15 clearly and sharply from the card; but it is to be understood that the rollers may be cold, if preferred.

It will be seen from the foregoing description that although the device of this invention is exceedingly simple of construction it will be found of great utility in use to photographers, especially those of the itinerant class. Its use, however, is not to be limited 20 to embossing photographs, as it may be employed for embossing cards, letter-heads, and other articles and still be within the scope of the invention.

Having thus fully described my invention, what I claim as new, and desire to secure by 25 Letters Patent, is—

1. A device of the class described, comprising a supporting-frame provided with spaced guides, a die having its terminals slidably mounted upon the guides, means on the frame 30 for holding the die properly positioned over surface to be embossed.

2. A device of the class described, comprising an approximately U-shaped frame, a die having its terminals slidably mounted upon 35 the guides, means on the frame for holding the die properly positioned over surface to be embossed.

3. A device of the class described, comprising a frame composed of a gage and aligned guides having their opposed faces provided 45 with recesses, and a die provided with means to engage the recesses.

4. A device of the class described, comprising a frame composed of a gage and aligned guides having their opposed faces provided 50 with recesses, a die movable on the guides and provided with means to interlock with the recesses, and a clamping-bar for holding the guides against lateral yield with relation to the die. 55

5. A device of the class described, comprising a die, a supporting-frame provided with guides having notches, and pins disposed in the opposite ends of the die to engage the 60 notches.

6. A device of the class described, comprising a die having grooves at its opposite ends, a supporting-frame for the die provided with guides adapted to engage the grooves, and means for connecting the upper and lower 65 ends of the guides.

7. A device of the class described, comprising a frame provided with a gage having laterally-extending lugs, a die adjustably associated with the frame, and a clamping-bar co- 70 acting with the frame.

8. A device of the class described, comprising a frame provided with a gage having yielding terminals, laterally-extending lugs carried by the terminals, and a die adjustably 75 associated with the frame.

In testimony that I claim the foregoing as my own I have hereto affixed my signature in the presence of two witnesses.

EDWARD DANIEL MACFEE, JR.
